ATTORNEY

UNITED STATES PATENT OFFICE.

EMMA I. BATES, OF PARK RIVER, NORTH DAKOTA.

HAT-PIN SHIELD.

1,227,238.

Specification of Letters Patent. Patented May 22, 1917.

Application filed January 5, 1916. Serial No. 70,484.

To all whom it may concern:

Be it known that I, EMMA I. BATES, a citizen of the United States, residing at Park River, in the county of Walsh and 5 State of North Dakota, have invented certain new and useful Improvements in Hat-Pin Shields, of which the following is a specification.

This invention relates to hat pins and 10 more particularly to a hat pin shield.

The primary object of my invention resides in the provision of a novel protecting means or shield for removable association with the pointed end of a hat pin for preventing the possibility of persons, standing 15 near the wearer of the pin, from being injured.

Another object of my invention resides in the provision of a novel resilient means 20 carried by either the shield or the pin for removably holding these members in engagement with each other and in various adjusted positions.

A still further object of my invention resides 25 in the provision of a device of the character described that is simple in construction, efficient in operation and one that can be manufactured and placed on the market at a minimum cost.

30 Other objects as well as the nature, characteristic features and scope of my invention will be more readily understood from the following description taken in connection with the accompanying drawings and 35 pointed out in the claim forming a part of this specification.

In the drawings:—

Figure 1 represents a top plan view of my invention associated with the flattened point 40 end of a portion of a hat pin.

Fig. 2 represents the longitudinal sectional view of the protecting means or shield associated with the pointed end of a hat pin, in side elevation.

45 Fig. 3 represents a longitudinal sectional view of a modified form of my invention.

Fig. 4 represents an enlarged transverse sectional view of a modified form of my invention, illustrating to advantage the arrangement of the locking means with the pin and the shield therefor.

Referring more particularly to the drawings in which similar reference numerals designate corresponding parts throughout 55 the different views, I provide a hat pin shank 1 with a flattened pointed end 2, in

which is provided a plurality of uniformly spaced openings 3 for a purpose to be described.

Removably associated with the flattened pointed end 2 is my improved protecting means or shield. In the present instance the shield 4 is shown in a cylindrical form, although this formation is not essential to the efficient operation of the invention. One 60 end of the shield is opened while the opposite end is closed as illustrated by the numeral 5 and provided with small stencil aperture 6 for receiving the pointed end of the pin yet limiting its movement and preventing it from projecting through the closed end.

For the purpose of removably holding the shield in an adjustable locked position on the pin, I have provided my improved locking means. This means consists of a V-shaped locking element 7 formed preferably of resilient material; the arm of the element being bent downwardly at the vertex and terminates in an engaging knob 8, while the 75 opposite ends of the arm are bent outwardly in opposite directions to provide pivot projections 9. These projections 9 are pivotally mounted in oppositely arranged openings 10 in the shield so that the arms can be arranged in close relation with the inner surface thereof and so that the knob projects beyond the open end of the shield. When in this position the flattened pointed end which has a width substantially the same as 80 the diameter of the shield is engaged by the shield and pushed toward the shank to the desired position, and thereupon the knob 8 will engage one of the openings 3. The knob can be removed by exerting a finger 85 pressure on the free end of the locking element.

In Figs. 3 and 4 I have shown a modified form of my invention. In this instance, the shank 1 is enlarged into a tubular formation as illustrated by the numeral 12. The locking element 7 is pivotally mounted within the tubular end 12, the pivot projections 9 being pivotally mounted in oppositely disposed openings 13. Because of the 90 resiliency of the metal from which the element 7 is formed, these projections 9 will normally extend beyond the outer periphery of the tubular portion 12 and when the shield 4 is associated therewith, the free ends of 105 the projections 9 will engage oppositely disposed recesses 14 in the inner periphery of 110

the shield when the said recesses are arranged in alinement with the openings 13. To remove the shield 4 from the tubular end 12, the shield is engaged and pulled outwardly against the tension of the arm of the element 7 causing the projections 9 to press partially through the openings 13 in the tubular portions 12.

Although I have shown and described the 10 preferred embodiment of my invention, I desire it to be understood that I am not to be limited to the exact details shown, however, I desire that great stress be laid upon the arrangement of the pin and the shield as 15 well as the novel resilient locking means carried by one of the members for adjustable association with the other of the members for removably maintaining the members in engagement with each other for accomplishing 20 the purposes specified.

From the above description taken in connection with the accompanying drawings, it can be easily seen that I have provided a device that is simple in construction, containing 25 but a few simple parts that can be cheaply manufactured and assembled and when assembled can be placed upon the market and sold at a minimum cost.

It will be understood that the above description and accompanying drawings comprehend 30 only the general embodiment of my invention and that various minor changes

in detail of construction, proportion and arrangement of the parts may be made within the scope of the appended claim and without 35 sacrificing any of the advantages of my invention.

Having thus fully described my invention, what I claim as new and desire to secure by Letters Patent is:—

40 A device of the character described including a pin having one end flattened and pointed and the flattened portion provided with a plurality of uniformly spaced openings, a cylindrical protecting shield arranged about the flattened pointed end, a V-shaped resilient locking member, pivot projections extending in opposite directions from the free ends of the member and pivotally mounted within the inner surface of 45 the cylinder so that the sides of the member contact with the inner surface, the vertex of the member being curved toward the center of the cylinder and projecting beyond the outer edge, and a knob integral with the 50 vertex for adjustably engaging one of the openings in the pin.

55 In testimony whereof I affix my signature in presence of two witnesses.

EMMA I. BATES.
